JOHN GEORGE LEYNER, OF DENVER, COLORADO, ASSIGNOR TO THE J. GEO. LEYNER ENGINEERING WORKS COMPANY, OF LITTLETON, COLORADO, A CORPORATION OF COLORADO.

ROCK-DRILLING STOPING-DRILL.

1,082,162.

Specification of Letters Patent. Patented Dec. 23, 1913.

Application filed October 18, 1910. Serial No. 587,651.

To all whom it may concern:

Be it known that I, JOHN GEORGE LEYNER, a citizen of the United States of America, residing in the city and county of Denver and State of Colorado, have invented a new and useful Rock-Drilling Stoping-Drill, of which the following is a specification.

My invention relates to improvements in rock drilling stoping drills, and the objects 10 of my invention are, first, to provide an air-feeding abutment engaging stoping drill, in which the cylinder and its coöperating heads are secured together by resiliently yielding joints; second, to provide an abutment engaging air-feeding hand oscillating stoping drill with resiliently yielding connections between its various coöperating enclosing and supporting members; and third, to provide a simple automatically lubricating stoping drill that is provided with resiliently yielding connected parts that are so coöperatively united and arranged to permit its connecting parts to resiliently yield under severe strains, sudden shock and severe 25 falls that would tend to break their connecting parts. I attain these objects by the mechanism illustrated in the accompanying drawings, in which:

Figure 1 is a plan view of the improved 30 stoping drill. Fig. 2 is a vertical, longitudinal, sectional view of the same. Fig. 3 is a horizontal, sectional view of the hammer piston cylinder casing on the axial plane of the throttle valve, the said valve 35 being shown in full lines. Fig. 4 is a horizontal, sectional view through the valve chest of the cylinder casing, the valve and end plugs being omitted. Fig. 5 is a rear end view of the cylinder casing. Fig. 6 is 40 a vertical, transverse, sectional view thereof on the line 6—6 of Fig. 4. Fig. 7 is a bottom view of the same, showing the oil reservoir and passages connecting it with the cylinder. Fig. 8 is a side view of the throttle 45 valve. Fig. 9 is a view of the opposite side of the said valve. Fig. 10 is a transverse, sectional view thereof on the line 10—10 of Fig. 8. Fig. 11 is a vertical, longitudinal, sectional view through the ported portion of 50 the said valve. Fig. 12 is a vertical, transverse, sectional view of the back head in which the drill rotating handle is clamped. Fig. 13 is an end view of the rear cylinder head. Fig. 14 is a longitudinal, sectional 55 view of the same. Fig. 15 is an end view of

the combined front cylinder head and striking pin bearing. Fig. 16 is a horizontal, sectional view thereof. Figs. 17 and 18 are side and front views, respectively, of the drill chuck. Figs. 19 and 20 are front and edge views, respectively, of the side rod washer plate; and Fig. 21 is a side view of a hexagonal form of drill bit.

Similar letters of reference refer to similar parts throughout the several views.

Referring to the drawings, the numeral 1 designates the cylinder portion of the casing of my improved stoping drill, in which a hammer piston 2 is reciprocally mounted.

3 designates the front cylinder head, which is provided with a hub portion 4, that fits snugly but loosely into the cylindrical bore 5 of the cylindrical casing 1. The front cylinder head is provided with an axial bore of two diameters, in which a striking pin 6 of two diameter portions is mounted to move reciprocally a short distance. The smaller diameter portion 7 of this striking pin I term the piston striking end, and this end projects through the smaller diameter portion of the head into the axial bore of the cylinder 1 and into the reciprocal path of the hammer piston 2 far enough to be driven forward by the hammer piston on its reciprocal strokes. 85 The larger diameter portion 8 of the striking pin I term its drill bit striking end portion, and it fits reciprocally in the larger diameter bore of the front cylinder head, and it is adapted to have a short forward and rearward feeding movement of about a half of an inch to compensate for the automatic feeding movement of the stoping drill, and the rock drilling speed of the drill bit driving blows of the hammer piston. 90 The reciprocal movement of the drill bit striking end of the striking pin is defined by the adjacent end of a drill bit supporting sleeve 9, which I term the drill bit holding chuck, which is provided with a hub portion 10 that fits into the larger bore of the front cylinder head. This drill bit supporting chuck is provided with an axial aperture that is adapted to support the shank end of a rock cutting or crushing 100 drill bit, and this aperture may be made of a form to receive drill tool steel of any form of cross section. I have, however, illustrated the chuck with an axial aperture of hexagonal form, adapted to receive the 11

shank ends of hexagonal tool steel drill bits 11. The shank portions of the drill bits are used in the chuck in their natural bar and are without lugs or collars, and are not increased or diminished in size, and they extend loosely into the sleeve against the striking pin. The rock crushing lips 12 of the drill bit strike against the rock while drilling a hole in rock, as will be explained 10 more fully hereinafter.

10 The front head 3 is provided with oppositely extending air vent apertures 13, which are preferably positioned at the top and bottom sides of the same, and are adapted to 15 permit any air that may leak from the cylinder past the striking pin into the aperture in the head from cushioning the striking pin, thus preventing its striking the drill bit with the full force of the blow of 20 the hammer piston.

20 The hammer piston is a plain cylindrical plug-shaped piston, with flat ends and preferably without piston rings. Its reciprocal movement is defined by the striking pin 25 supporting front cylinder head, and a rear cylinder head 14, which fits against the rear end of the cylinder, and is provided with a hub portion 15 that projects into it a short distance. This rear cylinder head is also 30 provided with a rearwardly projecting hub extension, which is formed into two reduced step portions 16 and 17, as shown in Figs. 2 and 14. The step portion 16 is arranged to receive the forward end of an air-feed 35 tube 18, which fits snugly but loosely over it, and the step 17 is of smaller diameter and is provided with a collar end portion 19. The step 17 is adapted to receive and retain between its collar 19 and its adjacent step portion 16 an air-feed retaining ring 20, which 40 is a split expansive steel ring that is sprung over the collar portion 19 and fits within an axial recess 21, formed in the front end of the piston head 22 of the air-feed tube 18. 45 This piston head 22 is a plug-shaped circular piston head which is provided with a threaded axial aperture 23, in which a reduced threaded end portion on the inner end of a piston rod 24 is screwed. A washer 50 of metal or other rigid material is placed on the reduced threaded end of the piston rod against the shoulder 26 formed between the threaded portion and the body of the piston rod, and the adjacent end of the piston head is provided with a reduced step portion 28, around which a resiliently expanding steel ring 28^A is placed and over this spring ring 28^A the circumferential band portion of a cup shaped washer 29 55 of leather or other suitable material is placed. The body portion of this cupped washer is mounted on the threaded end of the piston rod between the metal washer and the adjacent end of the piston head. 60 The expanding ring 28^A acts to press the

leather washer against the circular wall of the piston bore of the air-feed tube. The front end portion of the air-feed tube extends into a sleeve 31 is secured to a sleeve 31, preferably by being expanded therein, which sleeve I term the back-head of the stoping drill. This back-head bears against the rear cylinder head, and on its opposite side projecting lug portions 33 are formed, and the front cylinder head, the drill bit supporting chuck and the cylinder casing are also provided on their opposite side portions with lug portions 34, which are also arranged in alinement with the lugs of the back-head. The lugs of these parts are all 70 provided with apertures 35, which are adapted to receive bolt-rods 36. These bolt-rods 36 extend loosely through the apertures in the lugs and are provided with heads 37 that fit against the outside of the lugs of 75 the chuck, which are provided with recesses 38 that are adapted to receive the heads of the bolts, opposite sides of which heads are adapted to fit between and against the sides of the recesses and hold the bolts against 80 turning in the apertures of the lugs. The opposite ends of these bolt rods extend through and beyond the lugs on the back cylinder head and through the apertured ends of a washer plate 39, which is mounted 85 loosely on the feed tube 18, and coil springs 40 are interposed between the plate 39 and the back head 31. The ends of the rods are threaded to receive nuts 41. The coiled springs are adapted to be compressed by 90 screwing the nuts 41 against the washer plate, and the tension under which the springs are thereby held causes them to exert an outward pull on the rods and also 95 a pressure upon the back head which clamps 100 the cylinder, its head portions and the chuck together in alinement and with a resilient pressure that permits each piece or all of them together to yield under torsional or 105 twisting strains, or sudden jars, thus preventing breakage or disarrangement of the 110 said parts and their interior coöperating members. In order to secure the nuts 41 of these bolts against accidental movement that would relieve the springs of their 115 adjusted tension, I provide their washer engaging faces with transversely arranged ribs or keys 42, which are adapted to be engaged by grooves 43 in the adjacent face of the washer plate, into which grooves the keys 120 slip as the nuts are turned on the rod against the plate, the nuts being finally stopped with their keys resting in the groove of the plate when the springs are compressed to the required tension to clamp the cylinder and its 125 heads and the chuck together.

The back head 31 is provided with a projecting hub portion 44, through one side of which a slot 45 is formed along the opposite edges of which two lugs 46 are formed, 130

through which a bolt 47 is extended, and is adapted to clamp the lugs and the sides of the hub together around one end of a hand operated lever 48, which is preferably partially threaded or is otherwise removably secured to it, and is arranged to be clamped tightly in it against accidental movement or displacement. The opposite end of this lever is turned at right angles to its length to form a handle that can be grasped by an operator easily and quickly in any position in which the stoping drill is placed. This handle is employed by an attendant to oscillate the stoping drill when in operation, as it is necessary that the drill bit be turned or moved or partially rotated in alternate directions while drilling rock, as will be described more fully hereinafter. The air-feed tube extends rearwardly from the back head and may be made of any predetermined length that will enable the stoping drill to be easily and quickly handled. I preferably make this air-feed tube about thirty inches long and its outer end is threaded and is adapted to receive a cap 49 through which the piston rod extends. This cap comprises a cylindrical portion, which fits over the end of the air-feed tube and a hub portion through which the piston rod 24 passes. The interior of the cylindrical portion is threaded adjacent to the hub end thereof to receive the threaded end of the air-feed tube. This cylindrical portion is slotted and apertured lugs 50 are formed on opposite walls of the slot, which receive a clamping bolt 51 by which the cap may be clamped upon the end of the tube against accidental displacement. The hub of the cap at its junction with the cylindrical portion is formed with a hexagonal wrench receiving portion 49A, as shown in Fig. 1. This piston rod 24 I term an abutment engaging piston rod, as it is adapted to be held stationary against any part of the side walls or of the floor or roof of the stope portions of mines, or against any suitable stationary block or other object that is made to act as an abutment for it, as will be more fully explained hereinafter.

A small air vent aperture 52 is formed through the shell of the air-feed tube, which is adapted to allow the air in the tube behind the piston to escape as the piston moves forward, and this aperture also permits the actuating air to exhaust when the piston reaches the limit of its outward movement. The piston rod extends from the piston head of the air-feed tube through and beyond the end of the air-feed tube a short distance, and its terminal end is tapered to a point, as shown.

The drill bit driving hammer piston 2 in the cylinder 1 is operated by a valve that is inclosed in a valve chest 56, which forms a part of and is preferably cast integral with it. This valve chest has a cylindrical bore 57, formed through it, which forms a valve seat for a stem and collar form of valve 58, which fits snugly but reciprocally in the said bore. The opposite end portions of this bore are threaded and plugs 59 are threaded to them. The outside ends of the plugs are provided with head portions that screw up against the ends of the valve chest, and these head portions are provided with surfaces adapted to receive a wrench for inserting the plugs into and for removing them from the valve chest. The valve comprises a stem portion having collar portions 61 and 62 at its opposite ends, and two collar portions 63 and 64 intermediate of its ends at predetermined equal distances from its ends and from the center of its length, said collars being arranged to cover two cylinder inlet ports 65 and 66 and to control two exhaust ports 67 and 68. The cylinder inlet ports 65 and 66 extend from the valve seat to the opposite ends of the hammer piston cylinder, while the exhaust ports 67 and 68 extend from the valve seat into an exhaust outlet aperture 69 formed in and along the top of the valve chest that opens to the atmosphere at the rear end of the valve chest. The air inlet ports are placed at each side of the center of the length of the valve seat, and are controlled by the inside collars of the valve, and centrally between them an annular entrance port 70 is formed, which port communicates with a conical valve seat 71, which forms a continuation of an air inlet port 72, which is formed in a hub 73 cast on one side of the cylinder casing. The entrance to this air inlet hub 73 is threaded and a bushing 74 is threaded in it, which is provided with an inwardly flaring tapering aperture in which the tapering end portion of an elbow 75 fits, the outer end of which is threaded to receive a hose coupling nipple 76. The valve seat 71 is provided with a throttle valve 77, which may consist of any suitable form of air controlling valve, but I preferably, however, use a valve having a tapered tubular portion which is seated in the tapered or conical seat 71, and which is provided with a port 78, which is adapted to register with the entrance port 70 in the cylindrical valve seat 57, a ground joint being formed between this tapering tubular valve and its tapering seat. The stem of the valve extends through a hub on the opposite side of the casing, and a handle 79 is secured to its projecting end, preferably by being bolted thereto by a bolt 80. A small air port 81 is drilled horizontally into the valve chest from the outside, and has its outer end closed by a plug. This port communicates with the tapered valve seat 71, so as to be controlled by the tubular throttle valve, and it is intersected by a substantially vertical drilled port 82, the entrance of

which is also closed by a plug, and this port 82 also intersects the inner end of a horizontal port 83, that is drilled into the end portion of the valve chest. This port 83 5 communicates with an annular groove 84, that is formed in the inner face of the rear cylinder head, which groove forms a distributing port from which extend a plurality of obliquely arranged ports 85, which 10 communicate with an axial chamber 86 in the rearwardly extending hub portion of the rear cylinder head, from which chamber the air acts directly on the piston head 22 of the piston rod 24 of the air-feed tube 18, and pushes it outwardly through the air-feed tube until it reaches its outer end cap, when the air escapes to the atmosphere 15 through the vent exhaust aperture 52.

The port 78 in the throttle valve 20 communicates with an axial port 78^A in the body of the valve, and the port 78^A communicates with the inlet port 72. A port 78^B is formed in the periphery of the throttle valve and extends from one side of the port 78 substantially a fourth of the way around the periphery of the valve. This port is adapted to communicate with the port 81 when, the valve is open or in the position shown in Fig. 3, so that air may pass from the port 78 to the port 78^B and thence through cylinder ports 81, 82 and 83 and ports 84 and 85 in the rear cylinder head to the cylinder head chamber 86, whence it acts directly against the piston 22. When the valve is 35 raised the air is cut off both from the air-feed cylinder and from the drill cylinder, and a slight groove or port 78^C is cut in the edge of the port 78 opposite the port 78^B. The object of this port 78^C is to admit air 40 through the ports 81, 82, 83, 84 and 85 to the interior of the air-feed tube 18, in order that it may act on the feed piston 22 and thus start the whole drilling engine and the feed tube 18 away from the piston and feed 45 the drill-bit against the rock before air is admitted to the hammer piston and consequently before the hammer piston starts to reciprocate against the drill-bit.

The valve is provided with an exhaust 50 port groove 78^D, which is open to the atmosphere at one end and which is arranged to permit the air to exhaust from the feed tube 18 back through the ports 85, 84, 83, 82 and 81 and this groove 78^D to the atmosphere.

55 The slide valve 58 is operated in the following manner: Ports 58^A and 58^B respectively are drilled in from opposite ends of the valve chest casing and parallel with the bore of said casing, as shown in Fig. 4, and 60 their outer ends are plugged. These ports are intersected by horizontal ports 58^C and 58^D respectively, which are drilled through from the outside of the chest into its bore, these holes entering the chest a slight distance 65 back of the inner ends of plugs 59,

which inner ends are reduced in diameter, as shown in Fig. 2, to permit the entrance of air to the chest. The inner ends of the ports 58^A and 58^B are intersected by vertical ports 58^E and 58^F respectively, which enter the hammer piston cylinder 5. Air entering the rear end of the cylinder through inlet port 65 throws the hammer piston forward, and when its rear end uncovers the port 58^E, air passes through said port and through ports 58^A and 58^C to the rear end of the valve chest and throws the valve 58 to the forward end of the chest, as shown in Fig. 2, thereby opening port 66 and admitting air to the forward end of the cylinder, while at the same time the air behind the hammer-piston exhausts through the ports 65, 67 and 69. The hammer piston is now thrown to the rear and when its forward end uncovers the port 58^F air is admitted to the chest in front of the valve through the ports 58^F, 58^B, and 58^D and the valve is thrown to the rear end of the chest, thereby opening port 65 and permitting the air in front of the hammer piston to exhaust 80 through ports 66, 68 and 69. 85

The end collars 61 and 62 of the slide valve are provided with small exhaust ports 61^A and 62^A respectively. It will be noted that the distance between the port 58^F and the forward end of the cylinder is less than the distance between the port 58^E and the rear end of the cylinder; this is in order that when the hammer piston has moved only a short distance on its rear stroke the said port 58^F will be opened and the slide valve thrown to admit air to the rear of the hammer piston in time to cushion the piston on its rear stroke and thus prevent it from striking the rear cylinder head 14. 90 95

An oil reservoir 87 is formed upon the bottom of the cylinder, into the opposite ends of which plugged core holes 88 are formed.

Passages 89 and 90 are drilled in from 110 opposite ends of the cylinder casing and on opposite sides of the oil reservoir to points substantially midway of the length of the reservoir, and the inner ends of these passages are intersected by drilled passages 91 and 92 respectively, which extend through the cylinder casing and into the cylinder, the outer ends of all of said passages being plugged. 115

Holes 93 and 94 are drilled up through 120 the bottom of the reservoir and intersect the passages 89 and 90 respectively, whereby communication between the oil reservoir and cylinder is established through the said passages 93 and 94, 89 and 90, and 91 and 92. By this arrangement of the passages the lubricating oil will feed to the cylinder when the drill is inclined either upward or downward. The reservoir is filled through an inlet hole 87^A. 125 130

The oil works from the reservoir to the cylinder in the manner above described, and the hammer piston which covers passages 91 and 92 at all times as it reciprocates, wipes it up and distributes it throughout the cylinder, from which it works into the valve chest through its ports to the slide valve 58. The stoping drill is adapted to be used in drilling holes at any required oblique 10 angle, as well as in horizontally inclined positions, and during the reciprocating movement of the hammer piston a small quantity of air will leak into the reservoir, and when the drill is inclined upward this 15 air may escape back into the piston through the ports 94, 90 and 92, and when the drill is in a reverse position the air may escape through the ports 93, 89 and 91, to prevent expanding air forcing oil out when the piston 20 is not in operation.

A complete description of the principle of the operation of this method of cylinder lubrication may be found in Patent No. 958,260, issued to me May 17, 1910, for cylinder lubrication.

The operation of my improved stoping drill is as follows: The elbow 75 is connected to a hose, which I do not illustrate, but which extends to a supply of compressed air of from about 60 to 100 pounds pressure, 80 which is admitted by the operator to the valve, which is reciprocated in its seat and admits compressed air alternately to the opposite ends of the cylinder to reciprocate the hammer pistons, and as the said piston reciprocates it impinges against the end of the striking pin 6, which is driven against the end of the drill bit, and drives it forward. The drill bit is fed forward into rock 85 by the air-feed tube, in the following manner: The attendant places the point of the abutment engaging piston rod against the floor or one of the side walls of the mine stope in which the drill is being used, or 90 against any suitable abutment, such as a block of wood, and then turns on just enough air to move the drill forward until the drill bit engages the rock. The port 78^c of the throttle valve opens communication between 95 the inlet and the port 81, which admits air to the piston 22 before air is admitted to the hammer piston cylinder, and thus allows the drill to be set before the hammer piston is actuated. The operator then turns 100 on the air with full force, which reciprocates the hammer piston and drives the striking pin against the drill bit, and the striking pin drives the drill bit against the rock; the operator then grasps the drill oscillating handle, and oscillates the entire stoping drill and drill bit with a partial rotative movement, the drill being pivotally supported by the point of the drill bit bearing against the rock and the point of the 105 piston rod bearing against the abutment.

The drill bit is forced against the rock with a constant and continuous pressure, and as the operator oscillates the entire stoping drill, the drill bit being partially rotated, it drills a round hole and is held by the air pressure on the piston head 22 against the rock and feeds into it and consequently drills a hole as fast as it is driven by the hammer piston and striking pin. When the piston head 22 reaches the outer end of the feed tube, the air in the tube exhausts through the hole 52 and the operator turns off the air by closing the throttle valve. He then pushes the air-feed tube down on the piston head and takes out the drill bit and substitutes for it a longer one, and then places this longer drill bit into and against the bottom of the hole already drilled, and replaces the point of the piston rod against its abutment, and again turning on the air, 110 drills the hole to the extent of the feeding distance of the air-feed tube, and repeats this operation until a hole of the desired depth is attained.

My invention provides a simple, thoroughly practical, and highly efficient stoping drill, that is economical in the use of air and one that is light enough to be easily and quickly handled by a single operator.

Having described my invention, what I claim as new and desire to secure by Letters Patent is:

1. A stoping-drill having a cylinder with a front cylinder-head and a rear cylinder-head, a tubular casing mounted on said rear cylinder-head, a feed-piston within said tubular casing, a plate loosely mounted on said tubular casing, side-rods connecting said front cylinder-head said rear cylinder-head and said plate, and coil springs about 100 said side-rods interposed between said rear cylinder-head and said plate, whereby said cylinder-heads and said plate are yieldingly clamped together.

2. A stoping-drill having a cylinder with a front cylinder-head and a rear cylinder-head provided with two step-like shoulder portions, a feed-piston, a tubular casing for the feed-piston secured upon one of said shoulder portions, means for supplying compressed air through said rear cylinder-head into said casing, a rim extension on the head of said feed-piston adapted to move over the other shoulder portion when said feed-piston is drawn within the casing, and a retaining-ring about the second shoulder portion.

3. A stoping-drill having a cylinder with a front cylinder-head and a rear cylinder-head provided with a rearward extension 125 having an axial chamber therein, means for supplying compressed air to and exhausting it from said chamber, a front shoulder on said rear cylinder-head fitting within the cylinder, a rear shoulder on said rear cylinder- 130

6
der-head, a feed-piston, a tubular casing for the feed-piston secured upon said rear cylinder-head, a plate loosely mounted on said tubular casing, and means connected with 5 said plate for yieldingly clamping said tubular casing and said rear cylinder-head to the front cylinder-head.

4. A stoping-drill having a cylinder with a front cylinder-head and a rear cylinder- 10 head provided with an annular groove on its front surface, a rearwardly opening axial chamber, and ports connecting said groove and said chamber; means for supplying and exhausting compressed air 15 through said groove and ports; a front shoulder on said rear cylinder-head fitting within the cylinder; a rear shoulder on said rear cylinder-head; a feed-piston; a tubular casing for the feed-piston secured upon said 20 rear shoulder; and means for yieldingly clamping said tubular casing and said rear cylinder-head to the front cylinder-head.

5. A stoping-drill having a cylinder with a front cylinder-head and a rear cylinder- 25 head provided with an annular groove on

its front surface, a rearwardly opening axial chamber, and ports connecting said groove and said chamber; means for supplying and exhausting compressed air through said groove and ports; a front shoulder on said rear cylinder-head fitting within the cylinder; two step-like shoulder portions on the rear side of said rear cylinder-head; a feed-piston; a tubular casing for the feed-piston secured upon one of said shoulder portions; a rim extension on the head of said feed-piston adapted to move over the other shoulder portion when said feed-piston is drawn within the casing; a retaining-ring about the second shoulder portion; and means for yieldingly clamping said tubular casing and said rear cylinder-head to the front cylinder-head.

In testimony whereof I affix my signature in presence of two witnesses.

JOHN GEORGE LEYNER.
